US00D734573S

(12) **United States Design Patent**
Dammkoehler

(10) **Patent No.:** **US D734,573 S**
(45) **Date of Patent:** **** Jul. 14, 2015**

(54) **FLOOR CLEANING MACHINE**

(71) Applicant: **Alfred Kärcher GmbH & Co. KG**,
Winnenden (DE)

(72) Inventor: **Denis Dammkoehler**, Backnang (DE)

(73) Assignee: **Alfred Kärcher GmbH & Co. KG**,
Winnenden (DE)

(**) Term: **14 Years**

(21) Appl. No.: **29/470,579**

(22) Filed: **Oct. 23, 2013**

(30) **Foreign Application Priority Data**

May 17, 2013 (WO) DM/080 953

(51) **LOC (10) Cl.** **15-05**

(52) **U.S. Cl.**
USPC **D32/16**
